CLAIM

The ornamental design for a safety label, as shown and described.

DESCRIPTION

FIG. 1 is a top plan view of the first embodiment of a safety label, showing my new design;

FIG. 2 is a top plan view of the second embodiment thereof;

FIG. 3 is a top plan view of the third embodiment thereof; and,

FIG. 4 is a top plan view of the fourth embodiment thereof. The broken line portion of the figure drawings is included to show environment that forms no part of the claimed design.
